United States Patent Office.

W. H. PENNOCK, OF MERMAID, ASSIGNOR TO HIMSELF AND W. H. GREENWALT, OF MILL CREEK HUNDRED, DELAWARE.

Letters Patent No. 103,364, dated May 24, 1870; undated April 28, 1870.

IMPROVEMENT IN CHURNS.

The Schedule referred to in these Letters Patent and making part of the same

To all whom it may concern:

Be it known that I, W. H. PENNOCK, of Mermaid, in the county of New Castle and State of Delaware, have invented a new and useful Improvement in Churns; and I do hereby declare the following to be a full, clear, and exact description thereof, which will enable others skilled in the art to make and use the same, reference being had to the accompanying drawing forming part of this specification.

My object is improvement in churning;

The invention consists in the construction and combination of parts, as hereinafter described.

In the accompanying drawing—

Figure 1 represents a vertical longitudinal section of the churn through the line $x x$, fig. 2.

Figure 2 is a top or plan view of the churn with the cover off.

Similar letters of reference indicate corresponding parts.

A is the churn, the lower portion of which is circular, the center of which circle is the center of the driving-shaft B.

This churn vessel is supported on a suitable frame which is marked C.

D and E represent the dashers, one of which revolves within the other.

These dashers are each composed of two head-pieces and two longitudinal bars attached to the ends of the heads.

The head-pieces of the dasher D are marked F.

Those of the dasher E are marked G.

H represents the bars of both dashers. These bars in form and position on their head-pieces represent oblique longitudinal sections of a hollow cylinder, the center of which cylinder would be the shaft by which they are revolved.

The dashers are permanently connected together at their ends, at the driving end by a socket-piece, I, into which the square end of the shaft B enters.

This socket is fast to the minor dasher E, and the head-piece F of the other dasher revolves round it.

I is a bevel-wheel which is fast to the shaft and meshes into the stud-wheel M.

This latter wheel engages with the wheel N, which is loose on the shaft, and has a sleeve-hub which passes through the end of the churn, with lugs on the inner end of the sleeve, which enter small holes or sockets in the head-piece F, by which that dasher is revolved, as seen at O O.

It will be seen that, by means of the gear-wheels the motion of the two dashers is in opposite directions. The dasher E revolves within D, while the bars of D sweep the inner circumference of the churn circle.

The opposite ends of the dashers are connected together by means of the pin P, the head-pieces being separated by the collar J, while the head of the pin forms a center by which both dashers are supported on the pivot-screw I.

From the manner in which the driving power is applied to the dashers, (by the crank K,) it will be seen that, by turning back the pivot-screw I, the dashers may be readily released and removed from the churn whenever it is necessary to do so.

The bars H may be perforated with holes or slots, as seen in the drawing, for more thoroughly agitating the cream and breaking the globules.

The opposing currents produced by the dashers moving in opposite directions results in the speedy conversion of the cream into butter.

When the dashers are removed from the churn the latter may be used for working the butter, if desired.

This mode of constructing churning is simple and cheap, and its advantages must be obvious to all butter-makers.

Having thus described my invention,

I claim as new and useful, and desire to secure by Letters Patent—

The spiral beaters H, arranged and operating substantially in the manner described.

W. H. PENNOCK.
